[57] CLAIM

The ornamental design for a can.

DESCRIPTION

FIG. 1 is an elevational view of a can showing my new design;

FIG. 2 is a top plan view;

FIG. 3 is a bottom plan view;

FIG. 4 is a sectional view taken on the line 4—4 of FIG. 1;

FIG. 5 is a sectional view taken on the line 5—5 of FIG. 1; and

FIG. 6 is a sectional view taken on the line 6—6 of FIG. 1.

The broken line showing in FIG. 2 is environmental only and forms no part of the claimed design.

FIG 4

FIG 5

FIG 6
